UNITED STATES PATENT OFFICE.

JOHN B. PITCHFORD, OF SAN FRANCISCO, CALIFORNIA, ASSIGNOR OF ONE-HALF TO WILLIAM T. GARRATT, OF SAME PLACE.

CUT-OFF-VALVE GEAR.

SPECIFICATION forming part of Letters Patent No. 310,310, dated January 6, 1885.

Application filed April 14, 1884. (No model.)

To all whom it may concern:

Be it known that I, JOHN B. PITCHFORD, of the city and county of San Francisco, and State of California, have invented an Improvement 5 in Cut-Off-Valve Gear; and I hereby declare the following to be a full, clear, and exact description thereof.

My invention relates to a mechanism by which steam may be cut off after the valve 10 has been opened to admit it to an engine-cylinder, and the speed of the engine regulated to suit the work to be done.

It consists of an equalizing arm or lever which is so connected with the valve-stem of 15 an engine that movement can be imparted to the valve from two different sources at the same or at different times, as may be required, for the purpose of opening and closing the valves and admitting and cutting off steam to 20 suit the load of the engine.

Referring to the accompanying drawings for a more complete explanation of my invention, Figure 1, Sheet 1, is a side elevation, showing the application of my invention to a 25 reversible engine with rotary oscillating valves. Fig. 2 is a longitudinal section of the steam-cylinder, steam and exhaust chambers, and a transverse section of the valves. Fig. 3 is a 30 view of the regulating mechanism or governor. Fig. 4 is a section of the cam and gear, taken through the plane of the axis of the shaft, showing also the forward and back eccentrics. Fig. 5 is a view of the equalizing-lever and a 35 valve rocker-arm. Fig. 6 is the opposite cam to that shown in Fig. 1. Fig. 7, Sheet 2, shows the application of the equalizing-levers to a Corliss engine. Fig. 8, Sheet 3, is a view showing the lever operated by an eccentric with an adjustable throw. Fig. 9 is a plan view of 40 the mechanism, showing the stationary and the adjustable eccentric. Figs. 10 and 11 show the manner of attaching the movable eccentric, and the slot allowing its adjustment.

A is an engine-cylinder, B the piston, and 45 C the piston-rod. D is the steam-chest, with the inlet D', and E is the exhaust-chamber, with discharge at F. The valves G extend transversely through chambers H, so formed at each end between the steam and exhaust 50 chambers that the valves by their oscillation may open communication from the steam-

chamber to the cylinder through the port I and passage J, and when turned to the proper point will open communication between the cylinder and the exhaust-chamber by means 55 of the curved passage K, formed upon one side of the valve. The valves are oscillated by rocker-arms L, fixed to stems projecting through stuffing-boxes in the ends of the valve-chambers.

M is an equalizing-lever, the center of which is suspended upon the pin at the outer end of the rocker-arm. The ends of this lever have pins, to which rods N N' are attached. The rods N connect with the block O, which is 65 actuated by eccentrics through the link P, thus giving a regular movement and a means for reversing in the usual manner. The rods N' connect with links Q, and these are actuated by cam-grooves R R'. These cam-grooves 70 are of such shape that during the first part of the stroke of the engine they simply hold the end of the lever M, with which they are connected, while the eccentric moves the other end, and thus opens the valve. At the point 75 where it is desired to cut off the steam from the engine the cam-groove acts to draw the end of the lever with which it is connected back until the valve is closed.

In order to adjust the point of cutting off to 80 regulate the speed of the engine, the cam-grooves, which are formed on opposite sides of a disk, have a gear, S, formed on the hub a little to one side. The cam-grooves and gear, being made in a single piece, are bored, so as 85 to turn loosely upon the engine-shaft, as shown in Fig. 4. Curved arms T have their outer ends pivoted to a disk, U, and their innerends are toothed, the teeth engaging those of the gear, as shown in Fig. 3. These arms have 90 weights V upon them, which draw them outward by centrifugal action when the engine runs fast, and thus turn the gear and the cam-grooves in a direction which causes them to act to close the valves sooner; but when the 95 engine runs slowly springs W act to draw the arms inward and turn the cam-grooves in an opposite direction, so that they will act later and leave the valve open longer. In the present case I have shown the two cam-grooves— 100 one for each end of the cylinder—cut in opposite sides of a disk, the hub of which has the

gear cut upon or fixed to it, as before described. Short sliding bars X move in a guide-block, Z, and have pins which enter the cam-grooves R R', by which they are moved. Their opposite ends are connected with the links Q by rods a.

I do not particularly claim or limit myself to the means for adjusting the cams which I have here described, as governors have been 10 constructed in a similar manner, and other devices may be applied to my gear which will adjust or regulate it equally well.

Fig. 6 shows the application of my device to a Corliss engine in which two steam-valves 15 and two exhaust-valves are operated from a central disk, b, which is actuated by an eccentric upon the main engine-shaft in the usual manner. In this case one end of the lever is connected with the disk and the other with 20 cam-grooves on the engine-shaft, similarly to those before described.

In Sheet 3, Figs. 8 to 11, I have shown an eccentric slotted so as to be moved upon the shaft by the centrifugal action of the weighted 25 arms, and thus increase or diminish its throw. In this case the main fixed eccentric c is connected with one end of the equalizing-lever and the adjustable eccentric d is connected with the opposite end of the lever. The action of this 30 eccentric as its throw is lengthened or shortened will be to increase or diminish the movement of the valve.

The invention is specially applicable to the independent double-ported steam-valves of the 35 Corliss type, as the movement required is much less than with a slide-valve, and the cut-off can take place on one valve at any time without affecting the valve at the other end of the cylinder. When used with a single slide-valve, 40 it is less effective, for the reason that it requires too great a travel of the valve, and consequently a large movement of the cam, and there is also a tendency to choke the exhaust-passage.

Having thus described my invention, what 45 I claim as new, and desire to secure by Letters Patent, is—

1. In an engine valve-gear, an equalizing arm or lever which is connected with the valve-

stem of the engine, a mechanism, substantially 50 as described, by which movement may be imparted to the valve through it from two different sources at the same time or at different times, and mechanism, substantially as described, for automatically varying the cut-off 55 point of the valve.

2. In an engine, a single rotary steam and exhaust valve for each end of the cylinder, rocker-arms fixed to the valve-stems, and equalizing-levers M, with their centers journaled on pins on the rocker-arms, together with cam-grooves on the main engine-shaft, connected with opposite ends of the equalizing-levers, substantially as herein described.

3. In an engine, the single rotary steam and 65 exhaust valves for each end of the cylinder, with rocker-arms and equalizing-levers, fixed eccentrics connected with one end of the equalizing-levers, and adjustable cut-off cam-grooves connected with the opposite ends of 70 the levers, substantially as herein described.

4. In an engine, single rotary steam and 75 exhaust valves at each end of the cylinders, with rocker-arms and equalizing-levers, fixed eccentrics connected with one end of the equalizing-levers, with intermediate reversing-links, and adjustable cut-off cam-grooves connected with the other ends of the levers, with interposed links by which the cut-off gear may be reversed or thrown out of action, substantially 80 as herein described.

5. In combination with the rotary valve of an engine, an equalizing arm or lever connected with the pin on the rocker-arm of the rotary valve at a point between the ends of said arm 85 or lever, an eccentric, and connection between said eccentric and one end of said lever, a grooved cam and connection between it and the other end of said arm or lever, and a governor connected with and controlling said 90 grooved cam, all substantially as described.

In witness whereof I have hereunto set my hand.

J. B. PITCHFORD.
